US00D866255S

(12) **United States Design Patent** (10) **Patent No.:** **US D866,255 S**
(45) **Date of Patent:** **** Nov. 12, 2019**

(54) **CONTAINER**

(71) Applicant: **Runway Blue, LLC**, Alpine, UT (US)

(72) Inventors: **David O. Meyers**, East Layton, UT (US); **John R. Omdahl, II**, Lindon, UT (US)

(73) Assignee: **Runway Blue, LLC**, Alpine, UT (US)

(**) Term: **15 Years**

(21) Appl. No.: **29/636,494**

(22) Filed: **Feb. 8, 2018**

(51) LOC (12) Cl. **31-00**

(52) U.S. Cl.

USPC **D7/413**; D7/376; D7/378

(57) **CLAIM**

The ornamental design for a container, as shown and described.

DESCRIPTION

FIG. 1 is a top front perspective view of an embodiment of a container;

FIG. 2 is a bottom front perspective view of the container shown in FIG. 1;

FIG. 3 is a front view of the container shown in FIG. 1;

FIG. 4 is a rear view of the container shown in FIG. 1;

FIG. 5 is a right side view of the container shown in FIG. 1;

FIG. 6 is a left side view of the container shown in FIG. 1;

FIG. 7 is a top view of the container shown in FIG. 1; and,

FIG. 8 is a bottom view of the container shown in FIG. 1. The broken lines are shown for the purpose of illustrating environmental structure and parts of the article that form no part of the claimed design.

1 Claim, 8 Drawing Sheets
